Des. 201,696
Patented July 20, 1965

201,696

INDIVIDUAL HAND PARTY TRAY

Riccardo Zorn, Via Conservatorio 15, Milan, Italy

Filed Aug. 14, 1964, Ser. No. 81,294

Claims priority, application Italy Mar. 11, 1964

Term of patent 14 years

(Cl. D44—10)

Fig. 1.

Fig. 3.

FIG. 1 is a top plan view of an individual hand party tray showing my new design;

FIG. 2 is a perspective view thereof, taken from the edge at the top of FIG. 1; and

FIG. 3 is a perspective taken from the edge opposite to that of the view in FIG. 2.

I claim:

The ornamental design for an individual hand party tray, as shown.
